POWDER DISPENSING CAN

Clauss B. Strauch, New York, N. Y.

Application April 13, 1934, Serial No. 720,460

6 Claims. (Cl. 221—62)

This invention relates to improvements in powder dispensing cans and more particularly to novel means for closing, agitating and expelling the contents of such cans.

It is well known that certain powdered materials have a tendency to clog the outlet of a can when such a receptacle is used for dispensing the powder, and various means have been designed to prevent such clogging.

The primary object of the present invention is to provide novel means designed not only to effectively close the container but to agitate the powder in the container and to facilitate the dispensing of the powder.

Another object is to furnish a novel cover for a powder container provided with manually operated means for closing the cover outlet and for agitating and dispensing the contents of the container.

With the foregoing objects outlined and with other objects in view which will appear as the description proceeds, the invention consists in the novel features hereinafter described in detail, illustrated in the accompanying drawing, and more particularly pointed out in the appended claims.

In the drawing:

Figure 1 is a vertical sectional view of a powder container provided with one form of my invention and showing the container in closed condition.

Figure 2 is a similar view of the upper portion of the container with the closing plug in opened position.

Figures 3 and 4 are detail vertical sectional views of the spout and of the container in inverted position, and illustrating the manner in which the plug and its stem may move from side to side to prevent the powder from clogging in the spout, and to expel all powder harbored within the cone.

Figures 5 and 6 are similar to Figs. 1 and 2 but showing a modification, Fig. 5 showing the plug in opened position and Fig. 6 the plug in closed position.

Referring to the drawing, and particularly to Figs. 1 and 2 thereof, 6 designates a conventional can body adapted to contain powder 7. In accordance with the invention the removable cover 8 of the can may have a substantially conical spout 9 provided with an outlet 10. This outlet is closed by a plug 11 which may be of frusto-conical shape to accord with the shape of the spout. The plug is secured to one end of a stem 12 which is rigidly united in 13 with arm 14 and an operating rod 15. The operating rod extends upwardly and out of the cover and termi-

nates at its external end in a finger piece 16. In order to hold the plug normally in closed position, the rod extends through a tube 17 which depends from the cover and has a bottom 18. A coil spring 19 is arranged in the tube and bears at one end upon the bottom 18 and at its other end upon an abutment 20 that is fixed to the rod and guided by the tube 17.

From Figs. 1, 2, 3 and 4 it will be readily understood that when the finger piece 16 is pressed toward the body 6 and the container is inverted, the plug and stem can be easily moved from side to side through slight rotating pressure on the finger piece 16, thereby agitating the powder in the spout and placing the plug 11 into the midst of the powder masses to be dispensed.

However, as soon as the finger piece is released, the spring 19 will act to return the plug to closed position and the plug in seating will be guided by the frusto-conical inner surface of the spout. While being released into the closed position, the plug 11 will expel and dispense all powder in its way.

Instead of mounting the stem upon an arm projecting from the rod, the stem 12a may be directly connected to the rod 15a as shown in Figs. 5 and 6. In this embodiment, the stem may be of elbow shape and its inner end can be pivotally secured to the inner end of the rod, as illustrated at 13a. Obviously, this modification will operate in substantially the same way as the structure shown in Figs. 1 and 2 with the distinction, however, that the plug 11a is capable of agitating and reaching all the space within the spout 9a, being capable of being moved sideways when rotated around the operating rod 15a by side pressure exerted upon the finger piece 16a and in the other direction by being moved in the joint 13a by gravity and shaking of the can.

While I have disclosed what I now consider to be some preferred embodiments of the invention in such manner that they may be readily understood, it is manifest that changes may be made in the details disclosed without departing from the spirit of the invention as expressed in the claims. I wish to substantiate such possible changes by stating that the spring does not need to be encased in a separate housing but can be so arranged that it presses above directly on the finger piece while it rests below on the external surface of the top of the can or in a more or less deep footing. The spring does not need to be of the push type but may be a pull spring fastened with one end to the top and with the

other to a lower part of the operating rod, which may be guided in its course by a separate bearing attached to the cover, between cover and body of the can or to the can itself.

5. What I claim and desire to secure by Letters Patent is:

1. A receptacle cover provided with an outlet spout, an internal plug for closing said spout, an agitating element arranged in the receptacle and connected to said plug, manually actuated means operatively connected to said element for use in moving the plug to open position, and means cooperating with the last mentioned means for yieldingly holding the plug in closed position, said spout having an inner surface tapering toward the outlet for guiding the plug into closed position.
2. A receptacle cover provided with an outlet spout, a plug for closing said spout, an agitating element arranged in the receptacle and connected to said plug, manually actuated means operatively connected to said element for use in moving the plug away from the outlet of said spout, and means cooperating with the last mentioned means for yieldingly holding the plug in closed position, the interior of the spout and the wall of the plug having complementary substantially conical surfaces, for guiding the plug toward the outlet of the spout and into closed position.
3. A receptacle provided with an outlet spout, a plug for closing said spout, said plug being movable in the receptacle toward and away from the outlet of the spout, an agitating element arranged in the receptacle and connected to said plug, manually actuated means operatively connected to said element for use in moving the plug to open position, and means cooperating with the last mentioned means for yieldingly holding the plug in closed position, said spout having an inner surface tapering toward the outlet for guiding the plug into closed position.

4. A receptacle provided with an outlet spout, an internal plug for closing said spout, a stem for actuating said plug, a rod connected to the stem for operating the latter and provided with an external finger piece, and means cooperating with the rod for normally holding the plug in closed position and the finger piece in a projected position, the rod and stem being pivotally connected to one another to permit the stem to wobble when the plug is being opened or closed. 5

5. A receptacle provided with an outlet spout, an internal plug for closing said spout, a stem for actuating said plug, a rod connected to the stem for operating the latter and provided with an external finger piece, and means cooperating with 15 the rod for normally holding the plug in closed position and the finger piece in a projected position, the rod and stem being rigidly connected to one another to permit the stem to wobble when the plug is being opened or closed, said spout 20 having an inner surface tapering toward the outlet for guiding the plug into closed position.

6. A receptacle having a spouted outlet portion, a plug arranged in the receptacle for closing the outlet of the spout, said plug being movable in 25 the receptacle toward and away from the outlet of the spout, an internal rod operatively connected to the plug for actuating the latter, a second rod operatively connected to the internal rod for operating the latter, a finger piece secured to 30 the second rod for use in actuating the latter, and a spring cooperating with said parts for yieldingly holding the plug and finger piece in predetermined positions, the last mentioned rod being freely turnable about its axis, and the first mentioned rod being swingable toward the sides of the receptacle for agitating the contents of the receptacle, and means cooperating with the plug for 35 guiding the same into closed position.

CLAUSS B. STRAUCH.
